UNITED STATES PATENT OFFICE.

FRANK ZOLDO, OF NEW YORK, N. Y.

DESIGN FOR JEWELRY—NAMELY, A FINGER-RING OR ARTICLE OF SIMILAR NATURE.

59,316.

Specification for Design.

Patented Oct. 4, 1921.

Application filed June 17, 1921. Serial No. 478,440. Term of patent 7 years.

To all whom it may concern:

Be it known that I, FRANK ZOLDO, a citizen of the United States, residing at New York city, in the county and State of New York, have invented a new, original, and ornamental Design for Jewelry—namely, Finger-Rings or Articles of Similar Nature, of which the following is a specification, reference being had to the accompanying drawing, forming a part thereof.

Fig. 2 is an edge view thereof.

I claim—

The ornamental design for jewelry, namely a finger ring or article of similar nature as shown.

In testimony whereof I affix my signature.

FRANK ZOLDO.
